[57] CLAIM

The ornamental design for a sports bag, as shown and described.

DESCRIPTION

FIG. 1 is a front elevational view of a sports bag, showing my new design, the rear view being a mirror image thereof; FIG. 2 is a top plan view thereof; FIG. 3 is a side elevational view, the opposite side being a mirror image thereof; FIG. 4 is a top plan view in the open position; FIG. 5 is a perspective view thereof; FIG. 6 is a side elevational view, the opposite side being a mirror image thereof; and, FIG. 7 is a bottom plan view thereof. The broken lines on claimed design represent conventional stitching.
